[57] CLAIM

The ornamental design for a radial spray valve, as shown and described.

DESCRIPTION

FIG. 1 is a front elevational view of a radial spray valve showing a preferred embodiment of our new design; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; and, FIG. 7 is a front elevational view of another preferred embodiment of our new design, the embodiment of FIG. 7 being identically constructed as the embodiment illustrated in FIGS. 1–6 except for the provision of an elongated cylindrical lower portion of the embodiment of FIG. 7 replacing the shorter cylindrical lower portion of the embodiment of FIGS. 1–6, the remaining views of the embodiment illustrated in FIG. 7 being substantially identical as the embodiment illustrated in FIGS. 1–6 except for the lower portion thereof.
